CLAIM

We claim, the ornamental design for a training card, as shown and described.

DESCRIPTION

FIG. 1 is a front elevation view of a training card, showing our new design in a flat position;

FIG. 2 is a rear elevation view thereof;

FIG. 3 is a top plan view thereof, the bottom plan view being a mirror image thereof;

FIG. 4 is a first side elevation view of the invention, the opposite side being a mirror image thereof; and,

FIG. 5 is a perspective view thereof, shown in a partially folded position.

The evenly spaced broken lines immediately adjacent to the claim represent the bounds of the claimed design, and form no part of the claimed design.

References to "side", "top", "front" and "rear" in the figure descriptions are not meant to require certain in-use orientation, the training card according to the claimed design may be used in any orientation.
